CLAIM

We claim the ornamental design for a stick light, as shown and described.

DESCRIPTION

FIG. 1 is a perspective view of a stick light according to our new design.

FIG. 2 is a front view of the stick light shown in FIG. 1.

FIG. 3 is a rear view of the stick light shown in FIG. 1.

FIG. 4 is a left side view of the stick light shown in FIG. 1.

FIG. 5 is a right side view of the stick light shown in FIG. 1.

FIG. 6 is a top view of the stick light shown in FIG. 1; and,

FIG. 7 is a bottom view of the stick light shown in FIG. 1.

The elements shown in broken lines form no part of the claimed design.

1 Claim, 4 Drawing Sheets
